DISPLAY MANIKIN

Constantino Costa, New York, N. Y.

Application July 30, 1949, Serial No. 107,725

7 Claims. (Cl. 223—68)

1

My invention relates to a new and improved manikin and in particular to a manikin which has an improved waist construction whereby the torso or upper part of the manikin can be adjusted at its waist relative to its lower part.

Display manikins are of two general types, namely, "stand" and "flexible." The "stand" manikins consist of one or more parts which are fixed rigidly to each other. The "flexible" manikins are made of parts which are movable relative to each other. It is much more complicated and expensive to make "flexible" manikins than "stand" manikins.

According to my invention, I provide a manikin which has an internal construction whereby the manikin can be used either as a "stand" or "flexible" manikin. The internal parts disclosed herein can be used in either new and in old manikins or various styles of manikins. In addition, the invention greatly reduces the cost and time of manufacture.

Other objects of the invention are disclosed in the annexed description and drawings which illustrate a preferred embodiment.

Fig. 1 is a partial perspective view of the upper plate of the manikin, together with the rod which is fixed to said upper internal plate. The bottom part of Fig. 1A is a top plan view of said plate;

Fig. 2 is partially in vertical elevation and partially in vertical section and shows the lower plate which is fixed to the lower part of the manikin, together with certain parts accessory to said lower plate. Fig. 2A is a top plan view of said lower plate;

Fig. 3 is an elevation which shows the ball and rod which constitute an element of the invention;

Fig. 4 is a side elevation of Fig. 3;

Fig. 5 is an elevation showing the assembly of the parts illustrated in Figs. 1 and 2 with the respective upper and lower plates abutting each other, corresponding to a "stand" manikin;

Fig. 6 is a perspective view of the device, with the parts thereof shown exploded;

Fig. 7 is a vertical end elevation, partially in vertical section, showing the improved manikin with the plates of Figs. 1 and 2 held in relative fixed and abutting position in order to use the manikin as a "stand" manikin;

Fig. 8 is an end elevation which shows said plates in vertical spaced relation and in different angular relations; and

Fig. 9 is a side elevation of Fig. 8.

As one illustration, the body of the manikin is made in two parts, which can be joined at the

2

waist of the manikin. These body parts comprise an upper body part or torso part A, and a lower body part Aa. These body parts A and Aa have identical rigid respective base members B and Ba fixed respectively thereto. These hollow, disc-shaped base members B and Ba are made of metal or any other material.

As shown in Fig. 6, the lower base member Ba has a vertical, depending, circular flange Ca and its upper face has a recess Ea at the edge of a through-and-through opening or perforation Da.

The lower plate 5 fits in the top recess Ea, and said lower plate 6 is fixed by suitable fastening means extend through holes 16 of plate 6 and holes Fa of base member Ba.

As shown in Fig. 2, the upper face of lower plate 6 is provided with a socket 7, which is open at its bottom and which has a top opening 9. The plate 6 is open at the bottom of socket 7, whose internal wall has the shape of a part of a sphere. A vertical and externally threaded pipe 10 is fixed to the lower face of plate 6, in alignment with the open bottom end of socket 7 and the corresponding aligned opening of plate 6.

A nut 11 removably engages the external thread of pipe 10. Said nut 11 is closed at its lower end, and it houses a compression spring 12. Rod 14 has a square or other non-circular cross-section. Said rod 14 has a reduced extension 15, which is fixed in a recess of ball 13.

When nut 11 is temporarily removed from pipe 10, the rod 14 can be moved into the position shown in Fig. 2, upwardly through socket 7. The nut 11 can then be screwed upon pipe 10. When spring 12 is under little or no compression, ball 13 can turn freely in socket 7. When nut 11 is screwed upon pipe 10 in order to subject spring 12 to suitable compression, the friction between ball 13 and the internal wall of socket 7 holds ball 13 in fixed selected position relative to socket 7.

When lower plate 6 is fixed to lower base member Ba, the nut 11 extends through the opening Da of lower base member Ba, so that nut 11 can be easily manipulated.

The upper base member B has an upstanding flange C, and it is provided with a recess at its bottom face, which is similar to recess Ea. Said upper base member B has an opening D.

The upper plate 1 has a hollow rod 4 fixed thereto by legs 5. Said plate 1 has holes 3, through which screws or other fastening mem-

bers may extend. Said upper plate 1 is fixed to base member B, at and abutting the bottom recessed face of said base member B. The hollow rod 4 then extends above the upper base member B and the legs 5 extend through opening D. The plates 1 and 6 may be made of metal or other material, and their shapes may vary.

If desired, the torso A and the lower body part Aa can be assembled with the plates 1 and 6 abutting each other, and with inner rod 14 extending through outer hollow rod 4. Said rods 14 and 4 preferably interfit, so that inner rod 14 cannot turn in outer rod 4, since said rods have non-circular cross-sections or other means to prevent such relative turning.

The upper plate 1 has a central opening 2, which has lateral extensions 2b. The lower plate 6 has lugs 8 which are fixed to the outer wall of socket 7. When plates 1 and 6 are moved to abut each other, the lugs 8 are passed through extensions 2b, and socket 7 extends through opening 2. A slight turning movement of plate 1 relative to plate 6 will then interlock said plates 1 and 6 by means of lugs 8, and nut 11 can be tightened to clamp ball 13 in socket 7, with rods 4 and 14 in vertical position. In such case, the device operates as a stand manikin.

If it is desired angularly to adjust the torso A of the manikin relative to its lower part Aa, the plate 1 is raised to a selected height above plate 6, so that the torso A is similarly raised above the lower part Aa. The outer rod 4 is thus slid upwardly relative to inner rod 14.

While ball 13 is loose and turnable in socket 7, the plate 1 is tilted to a desired angle relative to plate 6. The nut 11 is then tightened in order to clamp ball 13 in its adjusted position in socket 7, thus holding plate 1 in the desired angular relation to plate 6.

When thus adjusted, the outer rod 4 cannot turn on inner stop rod 14. Said inner rod stop 14 has a longitudinal recess 17, in which a rod 18 is located. Said rod 18 is pivoted at 19 to inner rod 14. When outer rod 4 has been thus adjusted longitudinally relative to inner rod 14, stop rod 18 is located as shown in Fig. 5, in which stop rod 18 is prevented from further downward turning by the lower edge-wall of recess 17, and rod 18 acts as a stop to prevent plate 1 from sliding down from its adjusted position. When in stop position, rod 18 may extend through an extension 2b.

Any suitable means can be used to hold outer rod 4 temporarily fixed to inner rod 14, when plate 1 is at the desired distance above plate 6 and at the desired angular relation to plate 6.

Fig. 7, the plates 1 and 6 abut each other, and the two parts A and Aa are vertically aligned and fixed to each other.

In Fig. 8, the plate 1 is spaced upwardly from and is parallel to plate 6, in the full-line position of plate 1. This shows how the height of the manikin may be adjusted. The broken line positions of plate 1 show its extreme angular adjustments.

For convenience, the plate B is designated as the first plate and plate Ba is designated as the second plate. When I refer to a manikin, I include all display devices and fixtures. Also, the invention is not limited to an adjustable waist connection of a manikin. Hence, the part A is designated as a first part and the part Aa is designated as a second part of the manikin or other display device or display fixture.

For convenience, the perforations or openings

2 and 9 are designated as longitudinal openings. I prefer to use four connecting legs 5, which are equally angularly spaced, in order to rigidly connect rod 4 to connecting member 1. The spaced legs 5 make it possible to tilt the reduced extension 15 between a pair of selected legs 5.

I have disclosed a preferred embodiment of my invention, but numerous changes and omissions and additions can be made without departing from its scope. The invention also includes the sub-combinations disclosed herein.

I claim:

1. A manikin which has a first part which has a longitudinal axis and a second part, a first connecting member fixed to a face of said first part and having a longitudinal opening, a second connecting member fixed to a face of said second part, and means for connecting said first member and said second member, said connecting means comprising a hollow first longitudinal rod positioned within said first part and attached to said first member, a socket fixed to said second member, a bearing member which is mounted within said socket, a second rod attached to said bearing member and extending through an opening in said socket and being slidably disposed within said first rod, said bearing member being turnable within said socket so as to incline said second part at a selected angle with respect to said longitudinal axis, means for manually releasably clamping said bearing member to said socket in said selected position of said second part, and means for manually releasably clamping said first rod to said second rod at selected relative axial positions thereof.

2. A manikin according to claim 1, in which said first rod is attached to said first member by a plurality of spaced legs, said second rod being located between adjacent spaced legs when said first connecting member is spaced from and inclined to said second connecting member.

3. A manikin according to claim 1, in which said means for clamping said bearing member to said socket consist of a pipe which has an external thread and which is fixed to said second connecting member and which extends away from said first connecting member, said pipe communicating with said socket through an opening of said second connecting member, a compression clamping spring located in said pipe, and a nut mounted on said pipe and movable on said pipe to compress said spring and clamp said bearing member to the inner wall of said socket.

4. A manikin according to claim 1, in which the inner wall of said socket has the shape of a part of a sphere and said bearing member is ball-shaped.

5. A manikin according to claim 1, in which said means for clamping said bearing member to said socket consist of a pipe which has an external thread and which is fixed to said second connecting member and which extends away from said first connecting member, said pipe communicating with said socket through an opening of said second connecting member, a compression clamping spring located in said pipe, and a nut mounted on said pipe and movable on said pipe to compress said spring and clamp said bearing member to the inner wall of said socket, the inner wall of said socket has the shape of a part of a sphere, and said bearing member is a ball which extends into said pipe.

6. A manikin according to claim 1, in which said opening of said first connecting member

has a key-extension, said connecting members being movable to abutting position, said socket having an external lug which is shaped to pass through said key extension when said connecting members are moved to abutting position.

7. A manikin according to claim 1, in which said rods have non-circular and interfitting cross-sections which prevent a relative turning movement between said rods.
